(57) **CLAIM**

The ornamental design for a light emitting diode module, as shown and described.

DESCRIPTION

FIG. 1 is an bottom front and right side perspective view of an light emitting diode module showing the new design; FIG. 2 is a front side plan view of FIG. 1, the back side being a mirror image thereof;

FIG. 3 is a right side plan view of FIG. 1, the left side being a mirror image thereof;

FIG. 4 is a top plan view of FIG. 1; and,

FIG. 5 is a bottom plan view of FIG. 1.

The broken line showing of the environment is for illustrative purpose only and forms no part of the claimed design.

1 Claim, 3 Drawing Sheets

FIG. 1

FIG. 2

FIG. 3
